Int. Cl. D17—01

U.S. Cl. D56—2

FIG. 1

FIG. 2

FIG. 3

FIG. 4

FIG. 1 is a front, top and left side perspective view of an organ showing my new design;

FIG. 2 is a view similar to FIG. 1 with the roll top in closed position;

FIG. 3 is a front elevational view; and

FIG. 4 is a right side elevational view.

The rear of the organ is conventional. The pattern on the lower front panel and the raised side panels is continuous throughout these areas.

I claim:

The ornamental design for an organ, as shown and described.
